Atty.

UNITED STATES PATENT OFFICE

JOHN F. WILLIAMS, OF BOSTON, MASSACHUSETTS

RAILING

Application filed April 3, 1930. Serial No. 441,187.

My invention relates to railings and particularly to railings of that class comprising a flexible cable or "rope" whose opposite ends are connected with posts, stanchions or other fixtures. More especially the invention relates to improvements in the construction of the cables of railings of the class indicated, and it has for its object to improve the construction thereof.

10 Railings of the type referred to are installed in theatres, public halls, churches, and like places where people congregate, and are usually employed as barriers that are desirably of attractive and ornamental appearance.

Usually a cable or rope of the class to which my invention relates has heretofore been constructed with a core of strong hemp rope having one, or each, end thereof permanently attached to a metal terminal structure provided at its free end with means such as a hook or eye through which it was connected with a post, stanchion or other fixture. It has been customary, also, to provide a tubular plush or pile fabric sheath or covering for the rope in order to give to the latter an attractive or ornamental appearance.

A disadvantage to the constructions heretofore proposed has been that the hemp rope was not fastened to the end terminal member or members securely enough to withstand the strains and loads sometimes imposed upon devices of this class. It has frequently happened heretofore that patrons of a theatre or the like would bear against the cables of a railing of this kind as heretofore constructed, and sometimes even sit upon the same, with the result that the hemp rope would be broken away from the end terminal structure.

My invention is designed to obviate this objectionable feature characterizing railings of this class as heretofore constructed and it provides an improved cable having the peculiar features of construction and mode of operation set forth and described in the following description, the several novel features of the invention being particularly pointed out and defined separately in the claims at the close thereof.

In the accompanying drawings:

Figure 1 is an elevation of a portion of a railing including a cable or "rope" constructed in accordance with my invention.

Figure 2 is a side elevation of an end portion of the cable illustrated in Figure 1.

Figure 3 is a central longitudinal sectional view of the portion of the cable illustrated in Figure 2.

Figure 4 is a section on line 4—4 of Figure 3.

Figure 5 is an elevation of the inner end of the head or cap member hereinafter referred to.

The embodiment of my invention herein illustrated consists of a pendant cable that is indicated generally at 1, Fig. 1, which is provided at each end thereof with a terminal structure 2 having a hook or anchor member 3 adapted to be separably engaged with an eye 4 provided upon a post 5, or other fixture in connection with which the cable 1 is employed.

The cable 1 comprises a core 6 consisting of a length of chain made up of metal links 7 arranged within a rubber hose 8 which is of slightly less length than the chain 6. This length of rubber hose 8 is preferably reinforced with textile fabric 9 in the ordinary fashion.

Through each endmost link 7 of chain 6 extends a cross-bar in the form of a screw 10 occupying apertures provided in two oppositely disposed lugs 11 and 12 provided upon the inner side or end of a cap member 13. The aperture 14 of the lug 12 is of approximately the same diameter as the outside diameter of the screw 10, while the opposite end of said screw is in threaded engagement with the lug 11 whose aperture 15 is threaded to receive the adjacent end of the screw.

The cap 13 is made with an exteriorly threaded body portion 16 on to which is screwed a ferrule 17 whose outer end portion is interiorly threaded to engage with the threads on cap 13.

To the outer end of cap 13 is rotatably connected the hook 3 and as herein shown the shank of this hook is made with a threaded socket 19 into which is screwed a threaded

stem 20 that is permanently fixed in position within said socket by a pin 21. At its inner end the stem 20 is made with a head 22 which permanently connects the hook 3 with the cap 13 so that said two elements are free to rotate relatively.

10 The length of rubber hose 8 is provided throughout its length with a tubular covering or sheath 23 made from plush or pile fabric which is preferably cemented in position upon the exterior of the hose 8. This tubular plush sheath 23 is preferably made slightly longer than the hose 8 so that its end portions 24 can be drawn inwardly and secured there 15 by means of stitches or threads 25.

20 Adjacent each end thereof the hose 8 is made at its opposite sides with apertures that are occupied by the opposite ends of a cross-bar 26, said cross-bar extending through the second link of chain 6 which adjoins the endmost link of the latter. This cross-bar 26 is secured permanently to the hose 8 by upsetting its opposite ends as indicated at 27, in Fig. 4, washers 28 being interposed between 25 the heads 27 and the wall of the hose 8. Also the cross-bar 26 may be shouldered to provide seats for washers 29 provided upon the interior of the hose.

30 After assembling the chain 7, hose 8 and plush fabric 23 the ferrule 17 is slid into position upon the fabric covering 23 and then the cap 13 is fastened by means of screw 10 to the endmost link 7 after which the ferrule 17 is slid forward and screwed on to the cap 13 and then fixed in that position by drilling 35 through ferrule 17 and into cap 13 to provide a socket into which is driven a locking pin 30. In this way the ferrule 17 is permanently fastened to the cap 13 so that it cannot be 40 removed therefrom without the employment of tools. It will also be clear that the hook 3 is permanently swiveled to the cap 13.

45 Railings of the character above described are commonly employed in theatres and other places of assemblage where they are used as barriers in proximity to which crowds of people often congregate so that such barriers are frequently subjected to rough usage and great strains. Also persons in proximity thereto often grasp and toy with the same and sometimes even sit thereon. It will therefore be clear that the above described construction provides an extremely strong and durable cable which cannot be injured or 50 disarranged when subjected to usage such as just described. Furthermore my improved cable may be made to present a very attractive and ornamental appearance.

60 A feature of advantage to the above described construction is that the hose 8 provides a very stiff yet flexible backing support for the pile fabric 23 so that the cable 1, Fig. 1, not only presents a smooth round appearance but it maintains its shape under pressure 65 applied exteriorly thereto. Another feature

of advantage consists in connecting the end portions of the chain 7 with the hose 8 as by means of the cross-bars 26 whereby said chain is maintained fully extended and in proper relationship with hose 8 which serves as a 70 housing therefor. Also the connection between chain 7 and hose 8 serves to hold the endmost links projecting partially from the hose so that the operation of connecting the cap 13 with the chain is facilitated.

75 Another feature of advantage is that the above described terminal structure houses the end portions of hose 8 and fabric 23 and cannot be manipulated to disengage or disassemble the parts thereof.

80 What I claim is:

1. In a device of the character described, in combination, a metallic cable; a flexible tubular housing for said metallic cable and an end terminal structure comprising a sleeve telescopically fitted upon the end portion of said tubular housing and connected with one end of said metallic cable, closure means for the outer end of said sleeve, and an anchor member rotatably connected with said closure means.

85 2. In a device of the character described, in combination, a link chain; a flexible tubular housing for said chain; and an end terminal structure comprising a sleeve telescopically fitted upon the end portion of said tubular housing and connected with one of the links of said chain, closure means for the outer end of said sleeve, and an anchor member rotatably connected with said closure 90 means.

95 3. In a device of the character described, in combination, a link chain cable; a flexible tubular housing for said chain cable; a cross-bar connected at its opposite ends with opposite sides of said tubular housing adjacent one end thereof, said cross-bar extending through one of the links of said chain cable near one end of the latter; and an end terminal structure comprising a sleeve telescopically fitted upon the end portion of said tubular housing and connected with the end of said chain cable, closure means for the outer end of said sleeve, and an anchor member rotatably connected with said closure 105 means.

110 4. In a device of the character described, in combination, a link chain cable; a flexible tubular housing for said chain cable, and an end terminal structure comprising a sleeve telescopically fitted upon the end portion of said tubular housing, a closure cap fastened to the outer end of said sleeve, a cross-bar upon the inner side of said cap extending through the adjacent endmost link of said chain cable, and an anchor member rotatably connected with said closure cap.

115 5. In a device of the character described, in combination, a link chain cable; a flexible tubular housing for said chain cable; a

cross-bar within said tubular housing having its opposite ends fastened to the opposite sides of said housing, said cross-bar extending through one of the links of said chain cable, and an end terminal structure comprising a sleeve telescopically fitted upon the end portion of said tubular housing, a closure cap fastened to the outer end of said sleeve, a cross-bar upon the inner side of said cap extending through the adjacent endmost link of said chain cable, and an anchor member rotatably connected with said closure cap.

6. A device of the character described constructed in accordance with claim 5 wherein said anchor member consists of a hook upon the outside of said closure cap whose shank is formed at its end with a threaded socket that is in threaded engagement with a stem extending loosely through an aperture provided in said closure cap and having at its inner end a head for holding said stem within said aperture.

Signed by me at Boston, Suffolk County, Massachusetts, this first day of April, 1930.

JOHN F. WILLIAMS.
